TENT-HEAD FIXTURE FOR INHALATIONAL THERAPY

Application filed November 22, 1930. Serial No. 497,379.

Our invention relates to a tent-head fixture for use in inhalational oxygen therapy, whether the oxygen be used alone or mixed with other gases (particularly carbon dioxide) in the treatment of pneumonia, asphyxia, and other disorders in which the respiration of air mixed with oxygen, or oxygen and other gases, is a therapeutic advantage, the object being to produce a unitary

10 inhalational apparatus constructed with particular reference to simplicity and compactness, convenience of transportation and operation, installation without loss of time, and efficacy in use.

15 With these ends in view, our invention consists in an inhalational tent-head fixture chiefly characterized by the installation of the injector and the refrigerating means in it to form a unitary structure to be transported, handled and operated as such.

20 Our invention further consists in an inhalational tent-head fixture characterized as above and having certain details of construction and combination of parts as will be hereinafter set forth and pointed out in the claims.

In the accompanying drawings:

Fig. 1 is a view in elevation of our improved inhalational tent-head fixture for 30 treating pneumonia, asphyxia, and allied conditions, with portions of the tent broken away;

Fig. 2 is a plan view thereof; and

Fig. 3 is a view of the head in vertical central section on the line 3—3 of Fig. 1, showing the use of ordinary water-ice.

In the particular embodiment of our invention herein shown and described, the injector consists of a threaded nozzle 10 adjustably mounted in a vertically-arranged tubular casing 11 to which oxygen alone under pressure, or oxygen mixed with other gases under pressure, is led from any convenient source of supply by a gas-pipe 12 comprising a coil 13. The injector-casing 11 is formed at its lower end with a flange 14 by means of which it is rigidly mounted upon the closed, flat, upper end of an upstanding, downwardly-opening, circular mixing-chamber 15 having in its said upper end a central

opening 16 into which the nozzle 10 of the injector projects downwardly. The upper end of the said injector-casing 11 is provided with a removable threaded cap 17 for access to the injector-nozzle 10, which is furnished with the usual transverse and horizontal gas-passages 18 and 19 into which the gas flows under pressure from the gas-pipe 12 aforesaid.

In the apparatus now being described, the 60 refrigerating-means consists of an annular water-ice container 20, of which the upstanding mixing-chamber 15 forms the inner wall.

Water-ice 21 fills the annular chamber surrounding the mixing-chamber 15, as shown 65 in Fig. 3. The gas-pipe 12 is located within this chamber, upon the bottom of which its coil 13 rests and is therefore brought into direct contact with the water-ice 21, which is introduced into the container 20 through a 70 removable cover 22 having a handle 23 and a depending annular flange 24 fitting snugly into a large circular opening 25 formed in a horizontal rim 26 secured to the upper edge of the ice-container 20 and projecting inwardly and outwardly over the same. The outer edge of the said rim 26 rests upon an annular flange 27 turned inwardly from the upper edge of the cylindrical body 28 of the fixture, whereby the said ice-container 20 is 75 suspended therein, there being sufficient difference between the diameter and depth of the ice-container and body to form an annular cooling-chamber 29 between their sides and a cooling-space 30 between their bottoms. 80

For convenience, the ice-container is provided just within its upper edge with a swinging bail-like handle 31 consisting of a heavy metal rod, the ends of which are pivoted in brackets 32 located at opposite points 85 within the container. When not in use, this handle is swung down into the position in which it is shown in Fig. 3. On the removal of the cover 22 the handle may readily be grasped for lifting the container out of the 90 body.

Rising centrally within the mixing-chamber 15 is a funnel 33, the upper end of which is centered with respect to the projecting lower end of the nozzle 10 of the injector, 100

while the flaring lower end of the funnel 33 opens downwardly into the tent 34 through a central opening 35 formed in the bottom of the body 28, the edges of the flaring portion of the funnel being secured as shown to the edges of the opening 35 as at 36.

For the admission of the expired air of the patient from the tent 34 into the annular cooling-chamber 29, the body 28 has formed in it a circular band of air-ports 37 through which the expired air is drawn into the said cooling-chamber 29, thence through the air-space 30, thence upward through an annular passage 38 between the flaring lower end of the funnel 33 and the lower end of the downwardly-opening mixing-chamber 15 which rises centrally within the ice-container 20 of which it forms a part, such circulation of the expired air being induced by the draft created by the injector 10 which discharges into the top of the mixing-chamber 15. The moisture carried by the expired air of the patient as thus circulated and cooled, condenses in the cooling-chamber 29 and cooling-space 30 and falls to the bottom of the body and is caught and confined therein on a cup-like insulating pad 39 set within the bottom of the body and rising over the flaring portion of the funnel; the water so collected by the cup-like pad may be poured or drawn off or soaked up by a sponge or cloth. The pad 39 also prevents moisture in the air exhaled by the patient from condensing upon the lower surface of the bottom of the body and dropping upon the face of the patient.

The tent, which may be of any approved construction and which is provided, as usual, with one or more observation-openings 40, is held away from the body 28 of the fixture so as to provide a free passage 41 for the expired air in the tent into the port-holes 37 in the body, by a rectangular frame 42 to which the upper portion of the tent is secured. Above the said frame 42 the tent is provided with an annular band 43 of the tent-cloth fitting snugly around the body at a point above the said ports and clasped upon the body by a band 44 formed at its ends with perforated ears 45—45 receiving a clamping-screw 46.

The tent-head fixture is suspended, as shown, by three spaced brackets 47 secured to the top of the body, providing for the attachment of springs 48 secured to a horizontal suspension-bar 49, but the particular means of suspending our fixture forms no part of our invention and may be varied according to convenience.

It will be seen from the foregoing description that under our invention the injector and refrigerating-means, i. e., the ice-container, are installed within the tent-head fixture itself, the said tent-head being, in effect, a unitary structure.

Oxygen alone, or oxygen mixed with an-

other gas or gases (preferably carbon dioxide, which promotes deep breathing), according to the treatment indicated, is supplied through the gas-pipe 12 from any convenient source of supply and under any desired pressure. In its passage through the pipe 12, the gas is cooled prior to its admission into the injector, from the nozzle 10 of which it is sprayed into the upper end of the mixing-chamber 15 and into the funnel 33, creating such a suction as to draw the exhaled air of the patient from the tent 34 upward through the passage 41 and thence through the ports 37 into the cooling-chamber 29, where it comes in contact with the exterior surfaces or sides of the water-ice container 20, thence downward into the cooling-space 30, where it is further cooled by contact with the bottom of the ice-container 20, thence upward through the annular passage 38 around the flaring lower end of the funnel 33 into the mixing-chamber 15, where it is further cooled and drawn over the top of the funnel 33 and downward through the same, from which it is discharged in the form of a "breeze", so to speak, into the face of the patient. As the cooled and, therefore, dried or dehydrated exhaled air is drawn into the funnel, it is mixed with the gas from the injector, the commingling of the air and gas being continued in the funnel up to the time of the discharge of the mixture therefrom.

By locating the injector and refrigerating-means, whatever their specific character and arrangement, within the tent-head proper, the practice of inhalational oxygen therapy is greatly simplified and made much more convenient than with prior devices, in which the injection-means and refrigerating-means have been located exterior to the tent-head and indirectly connected therewith, such prior devices being clumsy to transport and manipulate and requiring much more space, often being in the way of access to the bedside of the patient.

We would have it understood that in practicing our invention, changes may be made in the tent-head fixture herein shown and described, without departing from our essential invention, which is characterized by making the injector and refrigerating-means organic features of the fixture.

We claim:

1. A tent-head fixture for inhalational therapy having a body, a removable ice-container located therein, a mixing-chamber rising within the said ice-container, an injector coordinated with the said mixing-chamber, means for supplying gas to the injector, and a funnel located within the mixing-chamber and opening downward through the head, whereby the expired air is drawn through the head and cooled therein and thence into the mixing-chamber and dis-

charged from the funnel, by the suction created by the said injector.

2. A tent-head fixture for inhalational therapy having a body provided with air-ports, an ice-container suspended within the body, from the sides and bottom of which it is separated by cooling-spaces, a mixing-chamber surrounded by the ice-container and opening downward, an injector coordinated with the mixing-chamber, and means for supplying gas to the injector, whereby the expired air is drawn from the tent through the said ports into the said cooling-spaces and thence into the mixing-chamber, from which it is discharged, by the suction created by the injector.

3. A tent-head fixture for inhalational therapy having a body provided with ports, an ice-container suspended within the body, from the sides of which it is separated by a cooling-chamber, a mixing-chamber surrounded by the ice-container and communicating with the said cooling-chamber, an injector coordinated with the mixing-chamber, means for supplying gas to the injector, whereby the expired air is subjected to the action of the cooling-chamber and thence drawn into the mixing-chamber by the suction created by the injector, and means for insulating the bottom of the body from the ice-container and cooling-chamber.

4. A tent-head fixture for inhalational therapy having a body provided with ports, a funnel rising within the center of the body and opening downwardly therethrough, an ice-container set within the body and smaller in diameter than the same to form an annular cooling-chamber between them, a mixing-chamber located within the ice-container and forming a part thereof, an injector mounted in the mixing-chamber, means for supplying gas to the injector, whereby the expired air is drawn through the said ports into the cooling-chamber and thence into the mixing-chamber and funnel by the suction created by the injector.

5. A tent-head fixture for inhalational therapy having a body provided with air-ports, a funnel rising from the center of the body and opening downward therethrough, an ice-container located within the body and dimensioned for producing cooling-chambers between the sides and bottom of the same, a centrally-located mixing-chamber rising within the ice-container and carried thereby, an injector applied to the mixing-chamber into which the funnel rises for coaction with the injector, and a gas-pipe mounted in the ice-container, extending therewith and connected with the injector, whereby the expired air is drawn by the suction created by the said injector from the tent suspended from the fixture-head through the said ports and cooling-chambers into the mixing-chamber and

funnel, from which it is discharged upon the patient.

6. A tent-head fixture for inhalational therapy having a body provided with a series of air-ports, a funnel rising centrally within the body, an ice-container within the body with cooling-spaces between them, a downwardly-opening mixing-chamber rising centrally within the ice-container and receiving the said funnel, an injector mounted upon the top of the mixing-chamber, and means for supplying gas to the injector, whereby the draft produced by the injector draws the expired air through the ports of the body and through the said cooling-spaces into the mixing-chamber and thence into the funnel, from which it is expelled upon the patient.

7. A tent-head fixture for inhalational therapy having a body provided with air-ports, a centrally-located downwardly-opening funnel carried by the body, an ice-container within the body with cooling-spaces between them, a centrally-located downwardly-opening mixing-chamber carried by the ice-container and receiving the said funnel, an injector mounted upon the mixing-chamber, means for supplying gas to the injector, and insulating-means, whereby the moisture in the expired air is prevented from condensing upon the bottom of the said body.

8. In an apparatus for inhalational therapy, the combination with a tent-head; of a tent suspended therefrom; an air-circulating passage provided in the said head and communicating at its respective opposite ends with the interior of the said tent for removing air therefrom and reintroducing the same therewith; refrigerating-means located in the said head and associated with the said air-circulating passage in the tent-head for cooling air passing therethrough; and a gas-injector opening into the said air-circulating passage in the said tent-head in such manner as to cause a forced draft therethrough to remove air from the said tent for being cooled by the said refrigerating-means and to force the now cooled air back into said tent, plus an admixture of gas from the said gas-injector.

9. In an apparatus for inhalational therapy, the combination with a tent-head; of a tent suspended therefrom; an air-circulating passage provided in the said head and communicating at its respective opposite ends with the interior of the said tent for removing air therefrom and reintroducing the same therewith; refrigerating-means located in the said head and associated with the said air-circulating passage in the tent-head for cooling air passing therethrough; a mixing-chamber communicating with the said air-circulating passage; and a gas-injector opening into the said mixing-chamber for creating a forced draft through the said passage, whereby air is removed from the tent and

cooled by the said refrigerating-means and returned, plus an admixture of gas into the tent.

10. In an apparatus for inhalational therapy, the combination with a tent-head; of a tent suspended therefrom; an air-circulating passage provided in the said head and communicating at its respective opposite ends with the interior of the said tent for removing air therefrom and reintroducing the same thereinto; refrigerating-means located in the said head and associated with the said air-circulating passage in the tent-head for cooling air passing therethrough; a gas-injector opening into the said air-circulating passage in the said tent-head in such manner as to cause a forced draft therethrough to remove air from the said tent for being cooled by the said refrigerating-means and to force 20 the now cooled air back into said tent, plus an admixture of gas from the said gas-injector; and means for insulating the bottom of the tent-head, whereby the condensation of moisture thereupon is prevented.

25. In testimony whereof, we have signed this specification.

YANDELL HENDERSON.
